INVENTOR,
Norman W. Nutt,

BY

Geo. P. Kimmel, ATTORNEY.

UNITED STATES PATENT OFFICE.

NORMAN W. NUTT, OF TRENTON, NEW JERSEY.

FUSE PLUG.

Application filed September 17, 1926. Serial No. 136,124.

The invention relates to an electrical thermal plug, and more especially to that class of electrical fuse plugs of the screw type, designed as an automatic cutout for electric circuits.

The primary object of the invention is the provision of a fuse plug, wherein the fusible element is confined within a closure, so that in event of the melting of the fuse there is no liability of the sparks escaping or flames spreading causing fires or accidents, the plug being of novel form, as it includes a minimum number of parts, which are readily and easily assembled and when in this condition the said plug will be compact and constitute a unitary structure.

Another object of the invention is the provision of a plug of this character, wherein the fusible element is confined and held within a chamber formed in an insulation shell or body in a novel manner, the latter being closed by a cap which is sealed upon the shell or body and has a peep opening so that the fusible element can be readily visible to ascertain whether or not it has become melted, when a short circuit occurs in the electrical circuit within which this plug is arranged, the fusible element being held fast within the shell or body in a unique manner and also the said shell or body and the cap are interlocked with each other and sealed in a novel manner.

A further object of the invention is the provision of a fuse plug of this character, wherein the insulating members are interlocked with each other and hermetically sealed to confine the fusible element, so that when the same becomes melted, there is no possibility of the escape of sparks or a flame, thereby preventing accidents and possibility of conflagration, the plug being of the screw type, the screw apron being held upon the plug in a unique manner and all of the parts of such plug are assembled in a simplified way.

A still further object of the invention is the provision of a plug of this character, which is extremely simple in construction, possessing but few parts and these being constructed, to enable the same to be assembled with dispatch and when in assembled relation to each other present a unitary structure, thoroughly reliable and efficient in its purpose, strong, durable, and inexpensive to manufacture.

With these and other objects in view, the invention consists in the features of construction, combination and arrangement of parts, as will be hereinafter more fully described in detail, illustrated in the accompanying drawing, disclosing the preferred embodiment of the invention, and pointed out in the claims hereunto appended.

In the accompanying drawing:

Figure 1 is a side elevation of a fuse plug, 65 constructed in accordance with the invention.

Figure 2 is a plan view looking toward the cap end of the plug.

Figure 3 is a side elevation, partly broken 70 away, showing in detail certain adjunct parts and the assemblage thereof.

Figure 4 is a vertical longitudinal sectional view through the plug.

Figure 5 is an inner face plan view of the 75 cap of the plug detached.

Figure 6 is a detailed plan view of the plug with the cap removed, showing the screw element and the fusible element assembled with relation to the body or shell of 80 the plug, the cap being removed.

Similar reference characters indicate corresponding parts throughout the several views in the drawing.

Referring to the drawing in detail, A designates generally the main body or shell of the fuse plug, B the screw ferrule and apron, C the removable cap or closure head and D the fusible element, the details of these being hereinafter more fully described.

The shell or body A of the plug is preferably made of insulating material, as for example porcelain and is of cylindrical cup shape to provide a fuse chamber 10, in which is located and confined a fusible element D, 90 which is in the form of a strip of soft fusible metal, one end thereof being soldered or otherwise permanently secured at 11 to a hollow contact rivet 12, the same being passed centrally through the outer closed 100 end of the body or shell A and clinched thereto at its peripheral edges as at 13. This fuse strip D is bent into substantially L-shape for a major portion of its length, while the other end is deformed to provide 105 a stepped terminal 14 for a purpose presently described.

The open end 15 of the shell or body A is cut into from the outer peripheral edge at intervals to provide alternate series of 110

notches 16 and radial ribs 17, respectively, as is clearly illustrated in Figure 6 of the drawing.

The inner peripheral edge 18 of the open end 15 of the shell or body A is formed with a slot 19 through which freely passes the fusible element D so that the stepped terminal 14 of the latter will be seated in one of the notches 16 and the extremity thereof lies against the external surface of said shell or body A as is clearly apparent in Figure 4 of the drawing.

The screw ferrule B is preferably made from relatively thin sheet metal to provide for an annular apron or sleeve 20 concentrically arranged exteriorly of the shell or body A and distorted to provide a screw thread, the inner edge of the sleeve 20 being cut into to provide a series of spaced, bendable tongues 21 which are turned inwardly to engage in the respective notches 16 at the inner end 15 of the shell or body A. These tongues 21 rest within the notches 16 as is clearly shown in Figure 6 of the drawing.

The cap C is preferably made from insulation material, for example porcelain, and is of circular contour having at its outer end a corrugated rim 22, while the inner end is in the form of a circular recess of a size to receive the ribs 17 on the inner open end 15 of the body or shell A. From the wall 23 of this circular recess extend radially disposed lugs 24 which are spaced apart and alternate with notches 25 therebetween, these notches 25 being designed to receive the ribs 17 of the shell or body A, while the notches 16 in the latter are designed to receive the lugs 24 of the cap C when the latter is placed upon the body or shell A into position as shown in Figure 4 of the drawing. The cap C centrally thereof is formed with an opening constituting a peep hole or window 26 which is covered with a transparent panel 27 of disc form, preferably made from mica and is confined within the central circular recess in the cap and rests upon the open end 15 of the body or shell A when the cap is in position upon the body or shell A as is clearly shown in Figure 4 of the drawing.

The outer end of the cap C is provided with a hexagonal shaped countersink 28, in axial alignment with the window or peep opening 26 and serves as an identification medium for the particular character of screw plug in the marketing of the same. The cap C and the body or shell A are joined together by an adhesive and interlocked by the coacting notches 16 and 23 and ribs and lugs 17 and 24, respectively, on said parts, the adhesive being in the form of a cement or other adhesive substance 29 placed at the juncture between the point of separation of said parts.

In the assemblage of the fusible plug the ferrule B is placed upon the body A, with

the terminal 14 of the fusible element D confined within one of the notches 16 of said shell or body A with one of the tongues 21, of the said ferrule B overlying the terminal 14. Thereafter the cap C is placed upon the open end 15 of the shell or body A with the ribs 17 engaged in the notches 23 and the lugs 24 engaged in the notches 16, it being understood, of course, that the transparent disc 27 is within the central recess in the inner end of said cap C and will rest upon the edge of the open edge 15 of the body or shell A, this assemblage being clearly disclosed in Figure 4 of the drawing. Thereafter the cement 29 is applied to the joint between these separable parts, namely the shell or body A, ferrule B and cap C and when hardened unites the parts and renders the same a unitary structure.

The fusible element D can be readily visible through the transparent disc 27 and the fusible plug assembled in the manner as hereinbefore described is screwed into an electric plug socket in the usual well known manner to close an electric circuit at the switch box or other point of an electrical layout or system. When the fusible element D is melted by reason of an overcharge or a short circuit in the electric layout or system, there is no possibility of the escape of sparks or a flame from the chamber 10.

From the foregoing it is thought that the construction and manner of use of the plug will be clearly understood, therefore a more extended explanation has been omitted.

What I claim is:—

1. A fuse plug, comprising a substantially cup-shaped body made from insulating material forming a fuse chamber opening through one end of the body, a contact in the closed end of said body, a strip like fusible element engaged at one end with the contact and extending through the chamber, said body being formed with spaced external notches circumferentially opening through the outer face and open end of said body to present radial ribs at said end, a screw ferrule removably embracing the body and having inturned tongues resting in the notches, the free end of the fusible element being clinched between the ferrule and body and resting in one notch, and an insulating cap of substantially circular contour having a recess receiving the open end of the body, the wall of the recess being formed with radial lugs common to and engaging the notches.

2. A fuse plug, comprising a substantially cup-shaped body made from insulating material forming a fuse chamber opening through one end of the body, a contact in the closed end of said body, a strip like fusible element engaged at one end with the contact and extending through the chamber, said body being formed with spaced external

- notches circumferentially opening through the outer face and open end of said body to present radial ribs at said end, a screw ferrule removably embracing the body and having inturned tongues resting in the notches, the free end of the fusible element being clinched between the ferrule and body and resting in one notch, an insulating cap of substantially circular contour having a recess receiving the open end of the body, the wall of the recess being formed with radial lugs common to and engaging the notches, and an adhesive substance joining the cap and body.
- 15 3. A fuse plug, comprising a substantially cup-shaped body made from insulating material forming a fuse chamber opening through one end of the body, a contact in the closed end of said body, a strip like fusible element engaged at one end with the contact and extending through the chamber, said body being formed with spaced external notches circumferentially opening through the outer face and open end of said body to present radial ribs at said end, a screw ferrule removably embracing the body and having inturned tongues resting in the notches, the free end of the fusible element being clinched between the ferrule and body and resting in one notch, an insulating cap of substantially circular contour having a recess receiving the open end of the body, the wall of the recess being formed with radial lugs common to and engaging the notches, and an adhesive substance joining the cap and body, the inner end portion of the cap presenting at the outer portion thereof an unbroken continuation of the outer surface of the body.
- 20 In testimony whereof, I affix my signature hereto.

NORMAN W. NUTT.
